INVENTOR:

HYMAN E. GOLBER

By: Oliver O. Martin.

HIS ATTORNEY.

UNITED STATES PATENT OFFICE.

HYMAN E. GOLBER, OF CHICAGO, ILLINOIS.

PENCIL.

Application filed September 15, 1921. Serial No. 500,879.

To all whom it may concern:

Be it known that I, HYMAN E. GOLBER, a citizen of the United States, residing at Chicago, in the county of Cook and State of Illinois, have invented new and useful Improvements in Pencils, of which the following is a specification.

The present invention has relation to lead pencils, and has particular reference to the type of mechanical pencils in which a stick of lead may be inserted and advanced by a simple rotation of some part of the pencil casing.

Several pencils of the type referred to have successfully reached the market, some having attained wide distribution, and most of these pencils have one feature in common, namely a propeller rod, which is movable forward and back by a simple rotation of an element or part of the body of the pencil. In order to reload such pencil it is necessary to turn this element a great number of times in order to retract the propeller rod, and after inserting a new stick of lead it is often necessary to do some more turning until the propeller rod reaches this new stick of lead.

The principal object of my invention is the provision of a pencil of the type referred to, and of such construction, that the refilling operation may be completely performed and the propeller rod correctly adjusted relative to the refiller lead, without resorting to such tedious and tardy turning operations. Another object is to provide a simple, substantial and inexpensive structure of pleasing appearance. A further object is to provide a mechanical pencil which will compare favorably in weight with the ordinary wooden pencil, as it appears before it has been shortened by resharpening.

In order to attain the objects just mentioned I have provided certain novel combinations, which I shall now proceed to describe, and drawings exhibiting structures in which the important features of the invention are embodied, are hereto annexed.

In the drawings:

Fig. 1 is a sectional side elevation of the pencil of my invention,

Figs. 2 to 7 are fragmentary and detail views of the pencil illustrated in Fig. 1.

Fig. 8 shows a similar pencil, but slightly simplified,

Figs. 9 to 13 illustrate parts of this modified form.

The casing of the pencil illustrated in Figs. 1 to 7 comprises a barrel 1 and a tip 2. These parts are made from wood and, when assembled, may resemble in appearance an ordinary wooden pencil having the usual round or hexagonal body. At the rear end of the barrel is mounted a ferrule 3, which also may be identical in shape with the ferrule used on common pencils, and it may in that case be fitted with the usual rubber eraser 4. The ferrule is, however, not permanently fastened, as in ordinary pencils, but it is made to fit the barrel tightly, and it is capable of removal in order to gain access to a magazine chamber 1^a, which extends into the rear end of the barrel. The front end of the barrel 1 may preferably be fitted with a light ferrule 5, capable of protecting the end of the barrel against wear and abuse, and from the front end extends a cylindrical bore 1^b into the barrel to a point near the magazine chamber 1^a.

The wooden tip 2 is conical in shape, and it is securely mounted on a light metal tube 7, which latter is adapted to support a stick of lead 6, and this tube is shaped at the front end to close tightly on the lead, so as to prevent rotation of the lead while writing with the pencil. This may be accomplished, as indicated in the drawing, by cutting a plurality of slits 7^a in the front end of the tube, whereupon this end of the tube is swaged down around an arbor a very trifle smaller in diameter than the lead, as well known to those versed in the art. The rear end of the tube 7 is perfectly smooth and of a diameter to fit the bore 1^b of the pencil barrel. As a consequence it is seen that the tip is attached to and removed from the barrel simply by sliding the rear end of the tube 7 in or out.

Aside from the very simple propelling mechanism, which will be described presently, the foregoing completes the description of the pencil. The magazine can accommodate several sticks of lead, and the ferrule is readily pulled off and again replaced when it is desired to remove a stick of lead. For the purpose of reloading it is only necessary to pull out the tip, and to insert the lead from the rear end of the tube 7, as in-

dicated in Fig. 2, or from the front, if desired, whereupon the tip is pushed back in place and the pencil is ready for writing purposes.

5 In the barrel bore 1^b is placed a square tube 10, and abutting the front end of this tube is firmly seated a plug 12, which in turn is shaped to maintain a rotatable clutch member 13 longitudinally immovable. It is
 10 noticed that this clutch member is shaped to engage the rear end of the lead guide 7. Within the square tube is placed a propeller screw 11, the rear end of which has been flattened to form a shoe 11^a, and this shoe is
 15 made wide enough to fit the tube 10 diagonally, as best shown in Fig. 4, whereby the screw is free to slide longitudinally within the tube, but held against relative rotation. The propeller screw is shown provided with
 20 right hand threads, and it is shaped to ride in corresponding screw threads 13^a of the member 13.

From the foregoing description it is seen that a rotation of the tip 2 to the right results in a corresponding rotation of the clutch member. As the latter cannot move longitudinally it is noticed, that such rotation has the effect of drawing the propeller screw forward, thereby in turn advancing the lead 6. This operation may be repeated until all the lead in the stick 6 is used up, whereupon the tip is withdrawn from the barrel and a new lead inserted, as indicated. If the structure had been made like other pencils of this type, it would have been necessary, before removing the tip to insert a new stick, to turn the tip to the left a great many times until the propeller screw had been fully retracted, but due to the novel
 30 features of construction herein presented, among which is included a very quick lead of the threads on the propeller screw, it is not necessary to resort to such slow turning movements in order to retract the propeller rod.

Having taken a stick of lead from the magazine and placed it in the lead guide of the tip, the operator may place his index finger on the end of the tip (in order to prevent the lead coming through) and push the tip back into place. It is found that the lead causes the screw to recede during this pushing movement, and that the clutch members become re-engaged, whereupon the pencil is
 35 ready and properly adjusted for use.

The details of the clutch members are best shown in Figs. 5, 6 and 7. The member 13 is made with a pair of prongs 13^b which, as mentioned, are shaped to engage a corresponding pair of notches 7^b of the lead guide 7. These prongs and the rear face of the tube 7 may conveniently be made somewhat beveled, substantially as shown in Fig. 5, in order that the parts may slip into proper engagement when the tip is pushed into place,

a result not difficult to obtain, because the member 13 ordinarily is turning while the tip is entering the barrel. The body portion of said member is made slightly smaller in diameter than the bore 1^b, in order that it may be free to rotate within said bore; it is made with an annular groove 13^c, and its rear end is further reduced in diameter, both for the purpose of fitting the plug 12. Through the latter is first bored a hole 12^a, which corresponds in size to the groove diameter 13^c, whereupon its rear end 12^b is re-bored large enough to accommodate the flange 13^d of the clutch member. Finally a T-slot milling cutter is sunk into the side of the plug, whereby the opening is cut, through which the clutch member is inserted. The plug 12 has been made slightly oversize, so that it can be driven tightly into the wooden barrel of the pencil, after the clutch member 13 first has been inserted, and when once it has been forced into place, it is evident that it will hold said member against axial displacement.

The structure of Fig. 8 is in most respects similar to the one already described, yet it is somewhat simpler and cheaper to manufacture. The barrel 30 may be exactly like the barrel of said hereinbefore described pencil. The tip 31 may also be identical in shape, but in this structure it is found that the rear end of the lead guide 32 has been swaged down around a threaded arbor, in order to provide screw threads for the propeller screw 33. It is an important point to note, that in these structures of my invention the propeller screw nearly fits the lead guide, having only very few one thousandths of an inch clearance within the guide. For this reason it is only possible to load the tip 31 from the front. The drawings show considerable clearance within the lead guides, but I wish it understood that this is incorrect, and is only resorted to in order to make the drawings clearer and more easily readable.

The plug 12 is in this pencil replaced by a plug 34, which differs from the former in the shape of the passage for the propeller screw, as best shown in Fig. 10. The rear end of this passage has been enlarged to a diameter equal to the diagonal distance within the square tube 35, and this enlargement is deep enough to accommodate the shoe 33^a of the propeller.

When the lead in the guide of this pencil has been fully used up a new stick of lead is taken from the magazine 30^a, whereupon the tip 31 is pulled out far enough for the shoe 33^a to lodge in the said enlargement 34^b. A continued pull causes the propeller screw to rotate in the screw threads of the tip, and in the said recess 34^b, and thereby to recede until it finally leaves the tip entirely. The lead is then inserted from the

front end of the tip, and the latter is pushed back into place, making the pencil ready for use. It has certain advantages to remove the tip entirely from the barrel, as it enables the owner of the pencil to clean the parts and to look through the tip to see if the passage through the tip is clear of lead fragments. On the other hand it may be found that the user will come to prefer a mechanism which does not come entirely apart, in which case the operation of reloading merely consists in pulling the tip out as far as it will go, and then pushing it back again, a very simple and quick operation, indeed. A simple way of providing a stop, which will prevent the entire disengagement of the tip, is illustrated in the drawing. The screw threads of the propeller do not quite reach the front end of the rod, as a consequence of which a small head 33^b is seen to remain. This head is incapable of passing through the screw threads of the tip, hence the tip cannot be entirely disengaged. A propeller rod having such a head must be inserted in the tip from the front end, whereupon it is passed through the plug 34, and then its rear end can be flattened to form the shoe 33^a. At the time the head of the propeller rod approaches the front end of the tip it may be found desirable to have the shoe of said rod still in engagement with the square tube, substantially as indicated in Fig. 9, in order to make certain that the rod can advance far enough to expel every remaining fragment of the worn out lead. In flattening the rear end of the propeller screw, to form the shoe 33^a, it is found that the spreading metal forms rounded corners 33^c. These corners are apt to dig into the edge of the plug perforation 34^a, and to cause the parts to bind, when the tip is being pulled out, and the shoe as a consequence revolves within the recess 34^b. By careful machining of said corners this difficulty could be eliminated, but I prefer to place a small anti-friction washer 36 between the shoe and the edge of the perforation, because of its cheapness, and for the reason that it offers a more durable wearing surface than would be obtained by permitting the corners of the rod to ride on the edge.

It was hereinbefore pointed out that the propeller screw of my invention substantially fits the lead guide, and I wish now to state that the outside diameters of this screw and of the stick of lead are approximately the same. These proportions are important, partly because my propeller rod is very much simpler and cheaper to manufacture than those ordinarily used, and mostly for the reason that the guide provides room only for one stick of lead, making a collision between two sticks of lead impossible, and making it also impossible for the end of the propeller to become jammed between the

lead and the wall of the guide, a condition usually found in pencils of this type.

The word barrel hereinbefore used has been chosen to denote the rear end of the pencil. It is barrel shaped so far as it surrounds the magazine, but it is not required to be otherwise barrel shaped. Nor does the barrel necessarily have to be long and the tip short. In the preferred form of my invention, as illustrated in the drawings, the joint between the barrel and tip is located at the beginning of the tip taper, because it had been found a convenient place, and for no other reason. If desired, the point of junction may be brought further back, causing the square tube to project when the pencil is pulled apart, in which case the plugs 12 or 34 would have to be suitably fastened to said tube. The part of the casing taken away from the barrel would then be added to the tip, causing the lead guide to be more, or perhaps entirely covered by wood. The only objection which I have found to such construction is that, when the writer presses very hard on the pencil, in writing, the rear end, or barrel, of the pencil is apt to be forced out of engagement with tip. In the structure shown in the drawings, the person using the pencil will hold the pencil at or above the joint, because the tip is too short to get a good hold of, and it is seen that, the harder he may press against the paper, while writing, the harder does he also press the parts of the pencil together.

I claim:

1. In a pencil, a two part casing, a propeller rod within the casing and advanceable by a relative rotation of the two parts, said rod retractable by a relative axial movement of the said parts. 100
2. In a pencil, the combination with a barrel and a tip, of a propeller rod advanceable within said barrel and tip by a relative rotation of the two and retractable within the parts by a relative axial movement of the said parts. 105
3. In a pencil, the combination with a barrel and a tip, of a propeller rod, and a stick of lead, the rod and lead advanceable by a relative rotation of the barrel and tip, the rod retractable in said tip by pulling the tip straight out of the barrel, and retractable within the barrel by pushing the tip back into place. 110
4. The combination with a barrel and a tip, of a propeller rod, means normally maintaining said rod non-rotatable relative to said barrel, means normally maintaining the rod rotatable relative to the tip, said latter means releasable by pulling the tip out of the barrel, whereby the rod is caused to recede within the tip. 120
5. In a pencil, a two part casing, a propeller rod movable within said casing, a clutch within the casing compelling the rod 130

- to advance in response to a relative rotation of the casing parts, said clutch separable by a relative axial movement of the parts, which movement compels a retraction of the 5 rod and clears the casing for reloading.
6. In a pencil, the combination with a barrel and a tip slideable into the barrel, of a propeller rod advanceable within the barrel and tip by a relative rotation of the 10 barrel and tip, the abutting faces of said barrel and tip forming a clutch which prevents said rod from being forced back by the pressure against the lead, in writing, said rod retractable by an axial disengaging and 15 reengaging movement of said clutch.
7. In a pencil, the combination with a barrel, a tip, and a stick of lead, of a propeller screw having substantially the same outer diameter as the said stick of lead, said 20 tip provided with a lead tube which also is substantially the same internal diameter as the screw and lead, the tip having screw threads in which the propeller screw is seated, the threads of the two parts steep 25 enough to permit the screw to spin in the tip when the latter is pulled out of the barrel.
8. In a pencil, a barrel, a tip slideable into said barrel, clutch members becoming interconnected by the insertion of the tip, thereby compelling the rod to advance in response to a relative rotation of the barrel and tip, said members again separable by pulling the tip out of the barrel, said pulling movement 30 operating to retract the said rod.
9. In a pencil, a barrel, a tip, a propeller rod slideable within the barrel and normally rotatable with the barrel, a nut engaging said rod and rotatable with said tip, whereby 35 a relative rotation of the barrel and tip causes the rod to advance through the said tip, means within the barrel and co-operating with the rod, when the tip is being axially withdrawn from the barrel to permit rotation of the rod within the barrel for the purpose of retracting the rod within the tip.
10. In a pencil, a barrel, a tip, a propeller rod slideable within and rotatable with said 40 barrel for advancement through said tip, but capable of independent rotation within the barrel at the end of its advance movement whereby an axial withdrawing move- 45
- ment of the tip relative to the barrel is made possible, during which movement the rod is caused to recede within the tip by an axial movement of the tip. 55
11. In a pencil, a casing made in two portions, a propeller rod movable within said casing, means operating to maintain said rod non-rotatable relative to one portion and rotatable relative to the other, said means made inoperative by pulling the casing portions apart axially, said pulling operation causing the rod to spin backward in the latter 60 casing portion. 65
12. In a pencil, a casing comprising a barrel and a tip, a threaded propeller rod seated in screw threads within the casing, said rod compelled to advance in response to a relative rotation of the barrel and tip, the screw threads of said rod being so steep 70 that a subsequent axial movement of the tip from the barrel permits a relative rotation of rod in the screw threaded portion of the 75 casing, causing the rod to be retracted through the said tip. 80
13. In a pencil, a two part casing, a threaded sleeve within the casing, a propeller screw rotatable with one casing part and independently rotatable of the other, whereby a relative rotation of the two parts causes the screw to advance until, when fully advanced, it becomes rotatable independently of both parts, the screw threads being so steep 85 that a subsequent axial movement permits the screw to spin relative to said sleeve and thereby to receive within said second casing part. 90
14. In a mechanical pencil, a propeller screw and nut, the threads of said parts steep enough to permit the one to spin relative to the other in response to a relative axial movement of said parts. 95
15. In a pencil, a two part casing, a threaded lead guide in one of said parts, a propeller screw non-rotatable in the other part, a stick of lead, said guide, screw and lead being of substantially the same diameter, the screw threads being steep enough 100 to permit the screw and guide to rotate relatively in response to an axial movement of the casing parts. 105
- In testimony whereof I have hereunto affixed my signature.
- HYMAN E. GOLBER.
